Primary Examiner—Nelson C. Holtje
Attorney, Agent, or Firm—Kenyon & Kenyon[57] **CLAIM**

The ornamental design for a face for a watch, as shown and described.

DESCRIPTION

FIG. 1 is a perspective view of a face for a watch showing my new design; and,

FIG. 2 is a top plan view thereof.

The broken-line portions of FIGS. 1 and 2 are for illustrative purposes only and form no part of the claimed design.
